UNITED STATES PATENT OFFICE.

JACOB A. HYLE, OF ATLANTIC CITY, NEW JERSEY, AND NEEVON H. SCOTT, OF PHILADELPHIA, PENNSYLVANIA, ASSIGNORS TO CONTINENTAL RAILWAY SUPPLY CORPORATION, A CORPORATION OF DELAWARE.

RAIL ANCHOR FOR RAILWAYS.

Application filed November 4, 1926. Serial No. 146,108.

This invention relates to new and novel improvements in one-piece rail anchors or anti-rail creepers designed to be secured to the base portion of railroad track rails, and 5 in engagement with stationary parts of the road bed for the purpose of preventing longitudinal displacement of the rails during the passage of the rolling stock thereover.

The prime object of the invention is to 10 provide simple, novel, economical, practical, durable and thoroughly efficient means formed from a single piece of high grade spring steel possessing the requisite maximum strength, which may be easily and 15 readily applied to the base of a track rail and securely retained in its proper operative or stationary position thereon, and which will always effectively grip the rail and co-operate with a stationary part of the 20 road bed to prevent any creeping of the track rail.

Another object of the invention is to so 25 construct the improved device that it will always maintain an extremely effective grip and a firm frictional engagement with the track rail under all conditions of service.

Further objects of this invention are to so 30 construct the novel rail anchoring device that it will successfully resist the creeping of the track rail; that it may readily be removed and re-applied any number of times and 35 always retain its effective tension and gripping power; that it furnishes the required bearing surface against the railroad tie and projects downwardly into the road ballast, and is so formed at the point where it extends into the ballast that the vibration and 40 wave motion of the track rail will push the ballast apart so that it will not be in constant and actual contact with said ballast, thus avoiding interference with the railway 45 electric signalling systems such as are now employed.

The foregoing and such other objects as 50 may appear from the ensuing description are attained by the construction, location, arrangement and combination of the parts hereinafter more fully described, illustrated in the accompanying drawings, and particularly pointed out in the claims appended hereto, it being understood that slight changes in the precise shape, form, proportions and minor details of construction may be resorted to without departing from

the spirit or sacrificing any of the advantages of the invention.

In the accompanying drawings forming a part of this specification it will be seen that:

Figure 1 is a side elevation of the improved device embodying our invention, 60 showing the device in contact with both sides of the base of a track rail.

Fig. 2 is a side elevation showing the device secured to one side of the base of a track rail, showing substantially its position 65 before being snapped into contact with the opposite side of the base of the rail, and

Fig. 3 is a perspective view showing the anchor device detached and removed from the track rail.

In the embodiment of our invention as illustrated, the numeral 1 designates a railway track rail, and 2 an underlying cross-tie forming a stationary part of the railway road bed and supporting the track rail, the 75 said rail having a tendency to creep, when subjected to the stress of the travel of the rolling stock thereover.

Our novel rail anchor is formed from a single round rod or piece of high carbon 80 spring steel of the desired or required length, and may be of any suitable diameter possessing the required strength, preferably about seven-eighths of an inch in diameter for a part of its length, and then reduced 85 to about five-eighths of an inch in diameter from a point intermediate its length to the opposite end thereof, that is, the large headed or jaw portion 3 formed at one end and being about seven-eighths of an inch in diameter is bent upon itself in the manner shown, and is adapted to be securely clamped to one edge of the track rail base, and the same diameter is allowed to continue until the point 5 is reached, when the 90 diameter is reduced to five-eighths of an inch, which diameter is continued throughout the remainder of its length.

It will be perceived that the shouldered portion 7 of the anchoring device rests in 100 contact with the lower face of one side of the rail base, and from said shouldered portion it extends downwardly a suitable distance to the point 8 where it is bent upwardly to the point 9, which is adapted to 105 also contact with the lower face of the rail base, thus forming a lateral and vertically disposed U-formation, and from the point

9 it is bent downwardly, as at 8' intermediate the U-formation, said downwardly bent portion terminating at the point 9' from whence it is bent outwardly and upwardly 5 as is clearly shown in the drawings, terminating with upwardly extended beveled end portion 10 adapted to snap into contact with the other side of the track rail base as is clearly shown in Fig. 1.

10 The body portion of the anchor is so formed that the large depending portion is adapted to rest and provide the desired bearing surface against the railway cross-tie 2, and the U-formation constitutes a 15 double bearing surface in contact with the lower face of the rail base, while the reduced portion of the body is so bent and formed as to provide a depending resilient or springy portion toward one end thereof, 20 for the purpose hereinafter described.

It will be seen that the lowermost portion of the U-formation will normally rest within the road ballast, and it is so formed and disposed that the vibration and wave motion 25 of the rail during the travel of the rolling stock thereover will cause the ballast to be pushed apart so that it will not be in close and constant contact with said ballast thereby preventing interference with the railway 30 electric signalling systems now employed.

In applying the anchor device to the track rail it is first placed in its proper position with relation to the rail with the inner end of its jaw or headed portion 3 in engagement 35 with the upper and outer surface of one side of the rail base, and its body portion and free end portion resting beneath the bottom of the rail, thus causing said outer end portion to be under a resilient upward 40 tension, then by striking the outer surface of the jaw or head portion with a spike maul or other suitable tool, said jaw portion is driven into its proper position, overlapping one edge of the rail base, while its outer free 45 end portion will rest in close proximity with the opposite end of the rail base, as is clearly shown in Fig. 2, when by imparting a holding blow to the rear part only of the depending reduced springy or resilient portion as 50 shown at 8', that is of sufficient force to jar the free end, will cause the outer end portion 10 to immediately snap upwardly into tight contact with the other edge of the rail base, as clearly shown in Fig. 1, the 55 anchor being so constructed that said outer end portion will maintain an intense grip or clamping action on the rail, and any tendency of the rail to creep will cause its downwardly extended portion to tightly 60 contact with the cross-tie and thus necessarily impart a twisting action to the anchor thereby materially increasing and intensifying its gripping action on the rail and thus 65 reducing the liability of the rail creeping under any and all conditions.

It will be understood that this anchor device may be formed by any suitable or desirable machine or in any manner most convenient and economical, the rod of spring steel from which it is made being heat treated. Further, that the rod may be made of any suitable or desirable dimensions throughout its length. 70

Having thus described our invention what we claim and desire to secure by Letters Patent is: 75

1. A single piece rail anchor comprising a jaw portion at one end, a depending resilient portion transversely disposed with relation to said anchor, said resilient portion being in contact with the lower face of the rail in longitudinal alignment with the rail, and an upwardly extended portion at its other end. 80

2. A single piece rail anchor comprising a jaw portion at one end, a resilient depending portion transversely disposed with relation of said anchor, said resilient portion being in contact with the lower face of the rail in longitudinal alignment with said rail and intermediate the ends of the anchor. 85

3. A single piece rail anchor comprising a jaw portion at one end, a depending U-shaped resilient portion transversely disposed with relation to the anchor and having double contact with the lower face of the rail in alignment with said rail, and an upwardly extended free portion at its other end. 95

4. A single piece rail anchor comprising a jaw portion at one end, a laterally and vertically disposed depending resilient U-snapped portion adjacent said jaw, a resilient depending portion intermediate said U-shaped portion, and an upwardly extended portion at its other end. 100

5. A single piece rail anchor comprising a thickened jaw portion at one end, a laterally and vertically disposed depending U-shaped portion having a double contact with the under face of a track rail intermediate the side edges of said rail, and a reduced portion within said depending portion terminating at the other end with an upwardly extended and beveled clamping portion. 110 115

6. A single piece rail anchor comprising a jaw at one end, an intermediate laterally depending resilient portion, a downwardly depending portion intermediate said laterally depending portion, and an upwardly and outwardly extended portion terminating with a beveled upright portion at its other end. 120

7. A single piece rail anchor comprising a jaw portion at one end, a laterally depending resilient U-shaped portion, a depending resilient portion intermediate said U-shaped portion, and an outwardly and upwardly extended portion terminating with an upright beveled portion at its other end. 125 130

8. A single piece rail anchor formed from a round spring steel rod with a thickened a round spring steel rod with a jaw portion jaw portion at one end, a laterally depend- 10 at one end, an intermediate laterally de- pending resilient portion, a reduced por- portion between said depending portion termi- 5 nation intermediate said laterally depending portion, and an upwardly and outwardly clamping portion. depending at the other end with a beveled extended portion at its other end.

9. A single piece rail anchor formed from
